UNITED STATES PATENT OFFICE.

ROBERT MORSE WITHYCOMBE, OF SYDNEY, NEW SOUTH WALES, AUSTRALIA.

ATTACHMENT FOR TOOTH-BRUSHES AND THE LIKE.

1,190,057.

Specification of Letters Patent.

Patented July 4, 1916.

Application filed July 18, 1913. Serial No. 779,779.

To all whom it may concern:

Be it known that I, ROBERT MORSE WITHYCOMBE, a subject of the King of Great Britain, residing at Sydney, in the State of

5 New South Wales, Commonwealth of Australia, have invented certain new and useful Improvements in and Relating to Attachments for Tooth-Brushes and the like, of which the following is a specification.

10 This invention relates to appliances for frictionally cleaning the teeth or massaging the gums and proposes a device having a block or head of solid material for working the gums and a clip upon which the said block or head is removably secured and which, in turn, may be detachably secured 15 on the handle of a tooth brush or equivalent holder and causes the massaging block or head to act with resilient effect on the gums, thereby the more efficiently discharging its 20 function.

An embodiment of the invention is illustrated in the accompanying drawings, wherein:—

25 Figure 1 is a perspective view showing a preferred construction as mounted upon the handle of a tooth brush; Fig. 2 is a similar view, but showing the device in detached relation; Fig. 3 is a plan view; and Fig. 4 30 is a side elevation.

Similar characters of reference designate corresponding parts throughout the several views.

In the embodiment disclosed, the device 35 is made of a length of spring wire which is looped at one end to form a socket which fits over the handle of a tooth brush or equivalent holder 10, the arms of the loop being coiled together at 18 so as to exert an 40 inward pressure upon the adjacent face of the handle or equivalent holder and the ends 19 of said arms being formed to exert an inward or lateral pressure against the opposite edges of said handle or holder.

45 The portions of the arms which lie against the face of the handle or holder opposite to that engaged by the coil 18 are crossed and bent forwardly into the plane of the coil 18, as shown in Fig. 4 and are thereupon 50 twisted together throughout a suitable extent, as at 20, the twisted part 20 bearing for the whole or a part of its length against the same face of the handle or holder which is acted upon by the coil 18. The 55 wire of which the loop is formed has its terminal portions extended beyond the

twisted portion 20 and formed to provide two parallel prongs 13 which are inserted in openings or recesses extending from the end face of the massaging block or head 15. 60

In using the device, the fore-finger is pressed against the face of the handle or holder opposite to that which is engaged by the coil 18 and the head 15 is held with suitable pressure against the gum and vigorously reciprocated both horizontally and vertically. The massaging effect thus induced is materially promoted by the fact that the head 15 has a resilient bearing on the gum due to the springiness of that part 70 of the clip which includes the twisted portion 20 and the prongs 13. In this way, the pressure with which the massaging head is applied to the gums is not of absolute character such as would permit a mere rubbing 75 of the gums. On the contrary, the massaging block, notwithstanding the uniform pressure of the fore finger against the handle or holder, can yield or spring to adapt itself to the contour of the gums, and this spring thrust which takes place in a direction at right angles to the plane of reciprocal movement of the massaging head, materially promotes the efficient toning 80 of the gums. On the contrary, the massaging block, notwithstanding the uniform pressure of the fore finger against the handle or holder, can yield or spring to adapt itself to the contour of the gums, and this spring thrust which takes place in a direction at right angles to the plane of reciprocal movement of the massaging head, materially promotes the efficient toning 85 of the gums.

Having fully described my invention, I claim:—

1. A device of the class specified comprising a member provided at one end with a spring socket adapted to fit over the end of a tooth brush or equivalent holder and at its other end with a pair of spaced longitudinal prongs adapted to carry a block of dental massaging material, the said member having a springy portion adjacent the said block of massaging material whereby said block may be caused to bear with resilient pressure upon the gums. 95

2. A device of the class specified comprising a member consisting of a single strip of spring wire bent to form a spring loop at one end of said member for the reception of an end of a tooth brush handle or equivalent holder, and a pair of spaced longitudinal prongs at the other end thereof adapted to carry a block of dental massaging material, the arms of said loop having a coil connecting the same and arranged to exert an inward pressure upon the adjacent face of the handle and having their terminals arranged to exert an inward pressure upon the opposite edges of the handle, 100 105 110

said arms including portions which, adjacent said terminals, bear upon the face of the handle opposite to that engaged by said coil and are thereafter bent forwardly into 5 the plane of the coil and continued to provide said prongs which are also disposed in the plane of the coil, the portion of the member adjacent said prongs being springy whereby the said massaging block may be

caused to bear with resilient pressure 10 against the gums.

In witness whereof I affix my signature in presence of two witnesses.

ROBERT MORSE WITHYCOMBE.
